EDWARD B. NEWILL, OF DAYTON, OHIO, ASSIGNOR TO GENERAL MOTORS RADIO CORPORATION, OF DAYTON, OHIO, A CORPORATION OF OHIO

CONE TYPE SPEAKER

Application filed December 26, 1930. Serial No. 504,707.

This invention relates to acoustical devices and particularly to that class of devices in the radio field known as loud speakers. The ideal cone in a loud speaker should move as a whole with a piston like action in order to reproduce the low notes or low sound frequencies. To produce a piston like action there is required a stiff cone which might ideally be one with a deep cross section, in the mechanical sense. On the other hand the ideal cone, figuratively, should break off into sections which move at varying higher frequencies than is practical for the whole cone, in order to reproduce the higher notes. Obviously, and as works out in production, these two requirements work against each other where resort is made to a single diaphragm only. Thus a single diaphragm is incapable of accomplishing the desired result, because a uniform structure throughout the diaphragm, that being essential in order to accomplish the desired movement of the diaphragm as a whole, responds to a certain frequency depending on the sensitivity or perhaps stiffness of the vibratory member.

By reason of the difficulties encountered, an acoustic device is provided that has more than one cone, and in which each may be specifically characterized for response to definite portions of the sound range. It is therefore one object of the invention to provide an acoustical device for use in connection with radio instruments that will respond with equal fidelity to the entire range of sound frequencies impressed upon the instrument for reproduction.

A further object of the invention is to provide a vibratile means for acoustical apparatus, that will respond to the range of sound vibrations without unduly augmenting any particular field thereof.

A further object of the invention is to provide baffle means for a nested diaphragm acoustical device.

A further object of the invention is to improve acoustical devices in general.

Further objects and advantages of the present invention will be apparent from the following description, reference being had

to the accompanying drawings wherein a preferred embodiment of one form of the present invention is clearly shown.

In the drawings:

Fig. 1 illustrates a longitudinal sectional view of a radio loud speaker illustrating one form of the instant invention.

Figs. 2 and 3 each illustrate by similar sectional view modifications of the invention from that illustrated in Fig. 1.

By reference to Fig. 1 it will be seen that the acoustical instrument here disclosed, comprises a frame 20 of somewhat conical form that supports at its base a grille plate 21, while an actuating motor 30 is secured at the smaller or opposite end of the frame 20 as at 22. The grille 21 may be secured to the frame 20 in any preferred manner as by means of the screws 23 threaded therethru and into a clamping ring 24. For purposes hereinafter to be pointed out, the grille 21 is apertured as at 25 and 26, thus leaving bridging portions 27.

The motor 30 may be of any desired form, but it is here preferred to illustrate it as of the electro-dynamic type in which there is a cup member 31 provided for a field frame, the bottom wall 32 thereof being apertured at 33 to receive a reduced portion 34 of a core of pole piece 35, also included in the magnetic circuit of the cup 31. For purposes of reinforcing and adding magnetic material to the device, a backing washer or clamp plate 36 is passed over the shank 34 of the core member against which the shank is turned over or riveted as illustrated at 37. In the annular space defined by the side wall of the cup 31 and the core 35, there is deposited a field winding 40 provided with leads 41 and 42, the winding 40 substantially filling the annular space except for a chamber 43 that is receptive of a compressible packing member 44 in the form of a ring just fitting within the cup 31, and notched at 45 to make way for passage of the leads 41 and 42. The cup 31 is closed at its open end, and thus tends to complete the magnetic circuit by means of

a magnetic ring 46, engaging the compressible member 44 and the edge of the cup 31 where it is secured in any desired manner.

The ring 46 is notched at 47 to make way for the leads 41 and 42, and is centrally apertured concentric with, and sufficiently larger than, the core 35 so as to provide an air gap 48 of annular form between the ring 46 and the core 35. The structure thus described defines the passive elements of the motor, completing the magnetic circuit about the field coil, the latter of which is firmly held 10 against axial movement of the core 35 by the compressible member 44 interposed between the ring 46 and winding 40.

The active elements of the motor, include a flared cylinder 50 forming a support for a 15 voice coil 51, and that is disposed for movement in the air gap 48 hereinbefore referred to. The voice coil is provided with leads 52 that are appropriately supported, and provide communication with binding posts 54 20 from which connection may be made to an appropriate part of the instruments as by leads 55. The flared portion of the cylinder 50 is concentric with and secured to the apex portion 56 of a conical diaphragm 57, and to this in any appropriate manner is secured 25 a driving spider 58 being centrally supported by a reduced portion 59 coaxially of the core 35, as by a screw 60 as is well known in the usual practice. The spider 58 is peripherally flanged at 61 that makes provision for the union with the apex portion of diaphragm 57, and tends to reduce the member 30 to a piston like structure. Exterior of the flanged portion of the cylinder 50 there is secured a second spider 65 which may be inwardly flanged or flared at 66 for attachment with the cylinder 50, and its peripheral edge 35 may be flanged or otherwise turned up at 67 for attachment to the apex portion 68 of a 40 diaphragm 69. An intermediate diaphragm 70 is also attached to the intermediate portion of the spider 65 as by means of its apical flange 71. The remote or base portion of the cones 69 and 70 are secured to the grille 21 45 in any preferred manner as at 72 and 73 respectively.

While the illustration of Fig. 1 is truly 50 illustrative of the principles of construction involved, it is seen that other means may be resorted to on details of construction, as for instance in the manner of attaching the diaphragms to the grille, or to the spider member, or other active part of the motor. As 55 an example, a single spider member may be used to provide a driving relation between the voice coil and the apex portion of the various diaphragms, instead of using the composite form as illustrated. However, it is believed that the constructional form illustrated is 60 preferable since it produces the results sought after, in that a fairly rigid piston-like structure is provided in accordance with the above stated objects.

In Figs. 2 and 3 there are illustrated modifications of the diaphragm arrangement,

In Fig. 2 the free edge diaphragm of Fig. 1 has been replaced by a diaphragm 57a that has its base portion attached to the grille 21 as at 80, substantially in the same manner as the attachment 72 and 73 of the diaphragms 65 and 70. The structure illustrated in Fig. 2, in substance is a step in a progression from the structure of Fig. 1 to that of Fig. 3, since the form there illustrated is substantially the same as illustrated in Fig. 2, except for the 75 intermediate diaphragm 70 which has been omitted. The elements of the motor, including the voice coil and spiders are essentially the same in each of the three forms illustrated. The remaining essential difference from those stated above reside in the piercing or formation of the grille 21. In each instance the grille is apertured as at 25 to provide a series of apertures in what might be called a peripheral row and opening into the space 85 between the concentric diaphragms, the apertures in each instance extending over an appropriate portion of the grille between the points of attachment substantially as illustrated so that the diaphragms may be loaded only to the extent desired. Depending on whether two or more diaphragms are attached to the grille, the apertures conform to one or more circular rows of openings in accordance therewith and the diaphragm 95 bases are attached at the bridging portions 27.

In each of the forms illustrated, the central area or region of the grille is provided with an enlarged opening or sound aperture 100 26 that is substantially concentric with the one or more rows of apertures 25, and aside from this the central aperture is so designed as to be of a diameter commensurate of the base of the smallest diaphragm attached thereto. It will be noted as in the instance of Fig. 2 where there has been shown a nest of three diaphragms, namely 57a, 70 and 69, that the apertures 25 of one annular row are staggered with respect to the apertures 25 110 of a concentric row. By so positioning the apertures in the grille the free flow of air movement from one side of the diaphragm to the other is substantially interrupted, which in effect increases the path of air movement thereof, thus acting in the nature of a baffle plate. That is to say, by staggering the apertures of the grille, air movement from the space between the diaphragm 69 and 70, over the forward edge of the diaphragm 70 to the space between it and the diaphragm 57a, or vice versa, is hindered sufficiently to produce the desired results, since the air movement must take somewhat a circuitous path in order to manifest in that 115 phenomena, and undesirable reverberation and mechanical noise of operation are thereby damped out, making for a clearer tone 120 product.

When an acoustical device of the form 125

illustrated is operatively coupled with a radio receiver, movements of the voice coil 50 will be transmitted to the spiders 58 and 65 or to the single spider if such be used which due to the union with the several diaphragms of the vibratile assembly, will reproduce with exactness the full range of sound impression to which the instrument is subjected. In the form illustrated, particularly that of Fig. 1, the spider 58 with its attached diaphragm 57 is more responsive to sound impressions of high frequencies than are those diaphragms concentric and larger than it, and in turn the largest of the nested diaphragms is slower to respond to motor movements and is thereby particularly adapted to reproduce sounds of low frequency, while the intermediate diaphragm is well adapted to the reproduction of sound frequencies of an intermediate range.

It is highly desirable that the diaphragms each be selected of a material, or fashioned, or formed, or otherwise prepared so that the independent range of sound response of each 25 diaphragm of the vibratile assembly will overlap the range of one or more of the others of the assembly, thus providing a blending of the sound products of each diaphragm which tend to eliminate the specific prominence of either frequency, whereby the ultimate sound products of the acoustic device will be natural and pleasing throughout all points in its range of reproduction. In Fig. 1 the vibrating response characteristics are 30 represented by varying the mass and length of the diaphragms 57 and 70, and the pitch of the diaphragm 69, relative to the other two. In Figs. 2 and 3, the result is contributed to by varying the pitch of the cones, and 40 may include use of different and appropriate materials, as for instance papers of different firmness or texture, represented by the various cross hatching of said cones.

While the form of embodiment of the present invention as herein disclosed, constitutes a preferred form, it is to be understood that other forms might be adopted, all coming within the scope of the claims which follow.

What is claimed is as follows:

50 1. In a radio loud speaker, the combination comprising; a motor, a vibratile mechanism actuatable by said motor, said vibratile mechanism comprising a plurality of conic diaphragms having their bases and apices 55 concentric; means securing the bases and apices with respect to said motor so as to be driven thereby.

60 2. In a radio loud speaker, the combination comprising; a frame; a grille and a motor supported by said frame; a spider supported by the motor, a plurality of diaphragms responding to widely separated sound frequencies and each independently 65 driven by said spider, one or more of said dia-

phragms being secured to said grille and spider.

3. In a radio loud speaker the combination comprising; a frame; a grille and a motor supported thereby; a driver operable by 70 said motor, a spider yieldingly supporting the driver; a plurality of diaphragms of conical form secured at their opposite ends to the grille and to the driver, the diaphragms being arranged concentrically and responding 75 to the same operative impulses of the said motor in different degrees according to high, low and intermediate sound frequencies.

4. In a radio loud speaker, the combination comprising; a motor and means for supporting the same; a plurality of diaphragms actuatable by the motor, some of which diaphragms are secured to the supporting means; a voice coil; a spider connected to the said coil providing an operable connection between the motor and the diaphragms; said diaphragms arranged concentric with the said voice coil, and means securing them to the said spider at increasingly remote portions thereof.

5. A radio loud speaker comprising in combination a frame supporting a motor, said motor including a movable part; a grille covering the frame and spaced from the motor; a plurality of concentric conical diaphragms of truncated form located between the grille and motor and secured to said grille to be actuated by said movable part, said grille being apertured at regions intermediate the attachment of the concentric diaphragms 100 whereby said grille will provide a baffle for the same.

6. In a radio loud speaker the combination comprising; a grille plate; a plurality of diaphragms secured at their bases to said grille; 105 and a motor connected to drive all of said diaphragms; said grille providing a baffle plate for said diaphragms.

7. The combination set forth in claim 6, wherein, the diaphragms are truncated cones 110 of different diameter and nested one about the other, a spider; and means securing the smaller ends of said cones to the spider so as to be coincidentally responsive to each operative impulse of the motor.

115 8. In a radio loud speaker having a motor and a driver actuated thereby, a vibratile assembly, comprising in combination; a plurality of truncated cones; a grille supported in parallelism with, but spaced from said driver; means nesting the cones in concentric form between the driver and the grille; and means securing said cones at their respective ends to the grille and the driver.

120 9. In a radio loud speaker having a motor and a driver actuated thereby, a vibratile assembly, comprising in combination; a plurality of truncated cones; a grille supported in parallelism with, but spaced from said driver; means nesting the cones in concentric 125 130

form between the driver and the grille; and means securing the truncated end of each cone to the driver at substantially concentric rings from a central point.

5 10. In a radio loud speaker having a motor and a driver actuated thereby, a vibratile assembly, comprising in combination; a plurality of truncated cones; a grille supported in parallelism with, but spaced from said driver; means mounting said cones in the space between the grille and the driver; and means securing the bases and truncated portions of the cones to the grille and driver respectively, at substantially the same respective planes of attachment.

15 In testimony whereof I hereto affix my signature.

EDWARD B. NEWILL.
